US0D1035641S

(12) **United States Design Patent** (10) **Patent No.:** **US D1,035,641 S**
(45) **Date of Patent:** **** Jul. 16, 2024**

(54) **COMPUTER**

(71) Applicant: **Siemens Aktiengesellschaft**, Munich (DE)

(72) Inventors: **Yu Xia Pan**, Chengdu (CN); **Ting Li Lan**, Chengdu (CN); **Zhan Bo Ren**, Chengdu (CN); **Chang Sen Chen**, Chengdu (CN); **Hai Gang Xiong**, Chengdu (CN)

(73) Assignee: **SIEMENS AKTIENGESELLSCHAFT**, Munich (DE)

(**) Term: **15 Years**

(21) Appl. No.: **29/836,451**

(22) Filed: **Apr. 27, 2022**

(30) **Foreign Application Priority Data**

Oct. 28, 2021 (CN) 202130708894.0
(51) **LOC (14) Cl.** **14-02**
(52) **U.S. Cl.** ..... **USPC** **D14/300**; D13/179

(57) **CLAIM**

The ornamental design for a computer, as shown and described.

DESCRIPTION

FIG. 1 is a front elevational view of a computer showing our new design;

FIG. 2 is a rear elevational view thereof;

FIG. 3 is a top plan view thereof;

FIG. 4 is a bottom plan view thereof;

FIG. 5 is a right-side elevational view thereof;

FIG. 6 is a left-side elevational view thereof;

FIG. 7 is a front, bottom and left-side perspective view thereof; and,

FIG. 8 is a front, top and right-side perspective view thereof. The broken lines in the drawings illustrate portions of the computer that form no part of the claimed design.

1 Claim, 8 Drawing Sheets
